UNITED STATES PATENT OFFICE.

WILLIAM F. BOUCHÉ, OF LANCASTER, NEW YORK, ASSIGNOR TO GOULD COUPLER COMPANY, A CORPORATION OF NEW YORK.

DYNAMO-DRIVING MEANS.

Application filed February 3, 1922. Serial No. 533,796.

To all whom it may concern:

Be it known that I, WILLIAM F. BOUCHÉ, a citizen of the United States, and resident of Lancaster, in the county of Erie and State of New York, have invented certain new and useful Improvements in Dynamo-Driving Means, of which the following is a specification.

The invention relates to improvements in 10 dynamo driving means and particularly to means for effectively driving a generator from an axle of a railway car, or the like. An object of the invention is the provision of an improved driving connection for the 15 generator of the shaft drive type in which the dynamo may be rigidly supported from the car body. The invention aims to simplify the driving arrangement, to render the same certain in operation under the varying conditions of operation and to avoid elements and constructions which may tend to cause trouble. Other objects and advantages of the invention will appear more fully herein-after in the following specification and be 20 particularly pointed out in the appended claims.

In order that a clearer understanding of the invention may be had attention is hereby directed to the accompanying drawings 25 forming part of this application and illustrating certain embodiments of the invention. In the drawings—

Fig. 1 represents a side view of one form of my device applied to the driving of a 30 dynamo, secured to a railway car body, from a car axle, certain parts being shown in section;

Fig. 2 is an enlarged vertical section 35 through the driving connections of the device shown in Fig. 1;

Fig. 3 is a plan view of the same partly shown in section;

Fig. 4 is a vertical section similar to that shown in Fig. 2, showing a modified form 40 of construction;

Fig. 5 is a plan view showing a further modification, and Fig. 6 is a side elevation of the parts shown in Fig. 5, certain parts being shown in section.

Referring first to Figs. 1, 2 and 3 of the drawings, the body of a railway car, indicated at 1, is provided at one end with a truck 2 having end sills 3 supported by the

axle 4 carrying the usual wheels 5. Secured to the body of the car is a frame work 6 rigidly carrying a generator 7, the armature of which is adapted to be driven by a short shaft 9 adapted to slide in bearings 10 in the direction of its axis, which bearings are rigid with the frame work of the motor. In the embodiment of the invention illustrated, shaft 9 carries a pin 11 adapted to engage a resilient metallic member 12 projecting from a disc 13 which is carried rigid with the rotating armature of the dynamo, this member 12 being adapted to give way or break in case the dynamo should be stopped for any reason while the car is still running and thus prevent breakage of the parts. If the distance between bearing 10 and casing 14, 70 (presently to be described), varies at any time, as when the car goes about curves, shaft 9 will slide through the bearing 10. Member 12 is long enough so that pin 11 will at the same time slide along it, and 75 member 12 will always engage the pin under such conditions of varying distance. The above described parts are all old.

A gear case 14 is carried by the end sill 3, gear case 14, in the form of the invention 80 illustrated, being provided with flanges 15 which are rigidly secured to the end sill. A jack shaft 16 is mounted for rotation in gear case 14 parallel to the car axle 4. One end of the jack shaft extends out of the gear 85 case and is driven from the car axle by a driving connection, such as a flexible chain or friction drive, which will permit movement of the car axle relative to its truck in the lengthwise direction of the axle and also 90 vertically as is required under operating conditions. In the embodiment of the invention illustrated a chain 17 is shown as running over sprockets 18 and 19 on the car axle and the jack shaft. The jack shaft 16 95 is provided at its opposite end, within the gear case, with a beveled gear 20 which meshes with a beveled gear 21 on the end of the propeller shaft 22 which extends at right angles to jack shaft 16, through the 100 head or sleeve 23 which is rigidly secured to gear case 14. Shaft 22 is connected to the intermediate shaft 24 by means of a universal joint 25, the opposite end of the shaft 24 being connected to the short shaft 9 by 105 means of a universal joint 26.

Provision should be made for adjusting the positions of jack shaft 16 and propeller shaft 22 to take up the wear in beveled gears 20 and 21. This may readily be accomplished by mounting the shafts in suitable bearings, as is well understood. In the form of device illustrated shaft 22 runs in roller bearings 27 which are mounted in members 28 and 29 which are screw-threaded into 10 suitable flanges at the opposite ends of sleeve 23, the arrangement being such that shaft 22 and gear 21 may readily be moved forward or back, in the lengthwise direction of shaft 22, to adjust the position of gear 21. 15 The jack shaft 16 is also mounted in any suitable manner for lengthwise adjustment. In the form of construction illustrated a ball bearing 30 of the self aligning type is shown as provided at one end of the jack shaft immediately adjacent to bevel gear 20. On the other end of the jack shaft a self aligning double row radial ball bearing 31 is provided accompanied by a ball thrust bearing 32. The ball race of this latter bearing is 25 mounted in an adjustable sleeve 33 which is threaded into its support 34. Accordingly by running the bearing sleeve 33 into or out of its support the jack shaft may be shifted in its axial direction. The edge 33^a of the 30 bearing sleeve extending beyond support 34 may be castellated and when the position of the sleeve has been adjusted it may be locked in such position by a tongue or pin secured to support 34 which will enter one of the castellations of the sleeve, this tongue or pin 35 not being illustrated.

The form of construction shown in Fig. 4 is the same as that previously described except that the gear case 14^a takes the form 40 of a housing cast integral with the end sill or forming a part thereof. In the form of construction shown in Fig. 2 a cover plate 35 may be used to cover one side of the gear case and in the construction shown in Fig. 45 a similar cover plate 35^a may be used.

In the constructions so far described various advantages are secured, including positive action, possibility of adjusting parts to take up wear, maintenance of the driving relation under all conditions of operation, simplicity of construction, etc. Also the disadvantage of a direct gear connection with the car axle, in which the parts are subject to great wear and tear, is avoided.

55 In the form of construction shown in Figs. 5 and 6 of the drawings the gear case 14^a is pivotally mounted from the end sill 3 so as to permit the same to swing towards and away from the car axle. In the embodiment 60 illustrated the gear case has an upwardly extending lug 36 which is pivotally suspended by means of pin 37 from arms 38 of a bracket 38^a which is rigidly secured to the end sill 3.

65 In this form of construction spring means

are preferably employed to tend to resiliently press the gear case away from the car axle.

In the form of construction disclosed, the bracket comprising arms 38 secured to end 70 sill 3 has a vertical flange 39 extending downwardly below the end sill through an opening in which extends a rod 40. This rod is provided with an eye 41 through which extends a pin 42 which is mounted in 75 ears 43 which are secured to gear case 14^a. Rod 40 is provided with an abutment 44 at its opposite end, this preferably being a nut 80 adjustably mounted on a screw-threaded portion of the rod. A spring 45 is coiled about the rod with one end pressing against the bracket extension 39 and the other end pressing against nut 44, this spring acting to resiliently pull the gear case away from 85 the car axle.

Normally the nut 44 is forced by spring 45 against an abutment 46 carried by the frame so as to permit a slight amount of slack in the belt or chain 17. If the axle moves relatively to the dynamo in such a way as to take up or more than take up this slack, suitable driving connection is still maintained between the axle and dynamo because the dynamo may swing to the left as viewed in Figs. 5 and 6, under the tension of 95 the spring 45. Means also are provided to prevent the gear case from swinging too far towards the axle at any time, as it might tend to do under running conditions, against the pressure of spring 45. If the gear case 100 were permitted at any time to move towards the axle sufficiently to slack up chain 17 to a considerable extent, the chain might jump off the teeth of one of the sprockets. Such action is prevented in the form of construction 105 illustrated by providing bracket 38^a with an extension 46 having a downwardly extending flange 46^a having an opening therethrough through which the outer threaded portion of rod 40 extends. A pair 110 of lock nuts 47 are positioned on the threaded end portion of rod 40 beyond flange 46^a, which nuts are adapted to abut against flange 46^a to act as a stop, whenever the gear case tends to move towards the car axle sufficiently 115 to slack chain 17.

It should be understood that the invention is not limited strictly to the details of construction described but is as broad as is indicated by the accompanying claims.

What I claim is:

1. In apparatus of the character described, the combination with a railway car body, a car truck with sills and axles, and a dynamo supported rigidly from the car body, of a 125 gear case supported from one of said sills, a jack shaft supported within said case and having one end extending out of the same, a flexible driving connection between said extended end and one of said car axles, a pro- 130

5 peller shaft extending into said case at right angles to said jack shaft, bevel gears within said case on said shafts, meshing together, and connections between said propeller shaft and dynamo.

2. In apparatus of the character described, the combination with a railway car body, a car truck with sills and axles, and a dynamo supported rigidly from the car body, of a gear case supported from one of said sills, a jack shaft supported within said case and having one end extending out of same, a driving connection between said extended end and one of said car axles, adapted to permit movement of said car axle lengthwise and vertically, relative to its truck, a propeller shaft extending into said case at right angles to said jack shaft, bevel gears within said case on said shafts, meshing together, yielding means to maintain the driving parts in proper relation, and connections between said propeller shaft and dynamo.

10 15 20

3. In apparatus of the character described the combination with a railway car body, a car truck with sills and axles, and a dynamo supported rigidly from the car body, of a gear case, means pivotally suspending the same from one of said sills, a jack shaft supported within said case and having one end extending out of the same, a flexible driving connection between said extended end and one of said car axles, a propeller shaft extending into said case at right angles to said jack shaft, bevel gears within said case on said shafts, meshing together, spring means for pressing said case away from said axle, and connections between said propeller shaft and dynamo.

25 30 35

4. In apparatus of the character described the combination with a railway car body, a car truck with sills and axles, and a dynamo supported rigidly from the car body, of a gear case, means pivotally suspending the same from one of said sills, a jack shaft supported within said case and having one end extending out of the same, a flexible driving connection between said extended end and one of said car axles, a propeller shaft extending into said case at right angles to said jack shaft, bevel gears within said case on said shafts, meshing together, spring means for pressing said case away from said axle, means to prevent excessive movement of said gear case towards said axle at any time, and connections between said propeller shaft and dynamo.

40 45 50 55

5. In apparatus of the character described,

the combination with a railway car body, a car truck with sills and axles, and a dynamo supported rigidly from the car body, of a gear case, means pivotally suspending the same from one of the said sills, a jack shaft supported within said case and having one end extending out of same, a driving connection between said extended end and one of said car axles, adapted to permit movement of said car axle lengthwise and vertically, relative to its truck, a propeller shaft extending into said case at right angles to said jack shaft, bevel gears within said case on said shafts, meshing together, yielding means to maintain the driving parts in proper relation, and connections between said propeller shaft and dynamo.

60 65 70 75

6. In apparatus of the character described, the combination with a railway car body, a car truck with sills and axles, and a dynamo supported rigidly from the car body, of a gear case, means pivotally suspending the same from one of said sills, a jack shaft supported within said case and having one end extending out of the same, a flexible driving connection between said extended end and one of said car axles, a propeller shaft extending into said case at an angle to said jack shaft, gear means within said case on said shafts, meshing together, spring means for pressing said case away from said axle, means to prevent excessive movement of said gear case towards said axle at any time, and connections between said propeller shaft and dynamo.

80 85 90

7. In apparatus of the character described, the combination with a railway car body, a car truck with sills and axles, and a dynamo supported rigidly from the car body, of a gear case, means pivotally suspending the same from one of said sills, a jack shaft supported within said case and having one end extending out of the same, a flexible driving connection between said extended end and one of said car axles, a propeller shaft extending into said case at an angle to said jack shaft, gear means within said case on said shafts, meshing together, a rod connected to said case and having an abutment thereon, spring means extending about said rod between said abutment and said sill, arranged to press said case away from said axle, and connections between said propeller shaft and dynamo.

95 100 105 110

Signed at Depew, in the county of Erie, and State of New York, this 30th day of January, A. D. 1922.

WILLIAM F. BOUCHE.
